United States Patent Office

Des. 196,887
Patented Nov. 12, 1963

196,887

AIRPLANE

Theodore R. Smith, Oklahoma City, Okla., assignor, by
mesne assignments, to Rockwell-Standard Corporation,
Coraopolis, Pa., a corporation of Pennsylvania

Filed Aug. 28, 1961, Ser. No. 66,525

Term of patent 14 years

(Cl. D71—1)

FIG. 4

FIGURE 1 is a side elevation of an airplane showing my new design;

FIGURE 2 is top plan view thereof;

FIGURE 3 is a front elevation thereof; and

FIGURE 4 is a perspective view thereof.

The characteristic feature of my design resides in the location of the wings at a substantially vertically centralized position on the fuselage in combination with the location of the engine nacelles at the upper portion of the fuselage, substantially as shown.

The dominant feature of the design resides in the portions shown in full lines.

I claim:

The ornamental design for an airplane, substantially as shown and described.
